US0D1061399S

(12) **United States Design Patent** (10) **Patent No.:** **US D1,061,399 S**
(45) **Date of Patent:** **** Feb. 11, 2025**

(54) **MOUNT FOR ELECTRONIC DEVICE**

(71) Applicant: **SPIGEN KOREA CO., LTD.**, Seoul (KR)

(72) Inventors: **Jinyong Choi**, Seoul (KR); **Jinsung Choi**, Seoul (KR)

(73) Assignee: **SPIGEN KOREA CO., LTD.**, Seoul (KR)

(**) Term: **15 Years**

(21) Appl. No.: **29/893,264**

(22) Filed: **May 26, 2023**

(51) **LOC (15) Cl.** **12-16**

(52) **U.S. Cl.**

USPC **D12/416**; D14/253

(58) **Field of Classification Search**

(57) **CLAIM**

The ornamental design for a mount for electronic device, as shown and described.

DESCRIPTION

FIG. 1 is a front, top, right side perspective view of a mount for electronic device showing our new design;

FIG. 2 is a rear, top, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings show portions of the mount for electronic device that form no part of the claimed design.

1 Claim, 8 Drawing Sheets
